UNITED STATES PATENT OFFICE.

BURTON S. HARRIS AND HOWARD M. JOHNSTON, OF TORONTO, ONTARIO, CANADA, AS
SIGNORS TO MASSEY-HARRIS COMPANY, LIMITED, OF TORONTO, CANADA.

REEL FOR HARVESTER BINDERS.

Application filed January 21, 1927. Serial No. 162,488.

This invention relates to the revolving reels used on harvester-binders to draw the standing grain towards the cutter bar. Such reels require to be adjusted both vertically and 5 backwards and forwards.

In narrow binders in which the reels require support at one end only, the problem of providing adjustment is a simple one, but with wide binders in which the reel must be 10 supported at each end, difficulty is experienced in bracing the bearing for the outer end of the reel shaft and in providing for its simultaneous movement with the bearing at the inner end, and our object is to devise 15 simple and effective means for that purpose.

We attain our object by providing a bail-shaped frame, on the ends of which the reel shaft is journalled. The ends of the frame intermediate its cross member and the shaft 20 are provided with journals. At the outer end of the reel the journal is journalled in a bearing slideable on a substantially horizontal guide supported from the grain deck of the binder. The journal at the inner end has a 25 bearing at the upper end of a substantially vertical swinging link. A hand lever is secured to the bail-shaped frame whereby the frame may be rocked to raise or lower the shaft or the link swung to move the frame as 30 a whole back and forth. Means are provided to releasably lock the parts as moved.

The invention is hereinafter more fully described and is illustrated in the accompanying drawings in which

Fig. 1 is a plan view of our improved reel;

Fig. 2 a side elevation of the same;

Fig. 3 a front elevation of parts of the same; and

Fig. 4 a cross sectional detail of the reel.

In the drawings like numerals of reference indicate corresponding parts in the different figures.

1 is a part of the grain deck frame of a harvester-binder of known type. The reel

45 2 is provided with a shaft 3, which is carried on the ends 4 of the bail-shaped frame, formed with the cross member 5. This bail-shaped frame is pivotally supported on an axis intermediate of the shaft 3 and the cross member 5.

50 At its outer end the frame is carried by a support 6 suitably secured to and braced from the outer end of the grain deck frame, and provided with the substantially horizontal guide 7 on which is adapted to slide a block 8 forming a bearing for the journal 9 extending from the

bail-shaped frame. At its other end the bail-shaped frame is pivoted at the upper end of the rocking link 10. This rocking link is preferably forked at its lower end and is fulcrumed at 11 on a suitable stationary part 60 adjacent the inner end of the grain deck.

A coil spring 12 secured at one end to the bail-shaped frame behind the link 10, and at its other end to a stationary part, serves to counter balance the weight of the reel, and 65 thus facilitates the rocking of the bail-shaped frame on its supports.

To enable the bail-shaped frame to be conveniently rocked, we secure to the end 4, adjacent the inner end of the grain deck, a hand 70 lever 13 extending rearwardly. To hold the link in any position, to which it may be swung for the purpose of adjusting the reel, we provide the lock bar 14 pivotally connected with the link and provided with a series of notches 75 adapted to be engaged with a keeper 15 secured to any suitable stationary part.

The end of the shaft 3, at the inner end of the grain deck, is journalled in a yoke 16, which is adapted to slide on the vertical guide 80 17 adapted to swing in a plane parallel to that of the link 10. This yoke has a pinion 18 rotatably mounted thereon, through which pinion slides a square driving shaft 19 adapted to be driven in a manner common in the 85 art. The gear wheel 20 on the end of the shaft 3 meshes with the pinion 18. The diagonal brace 21 is secured at its rear end to the end 4 of the bail-shaped frame, and at its other end, embraces the shaft 3. 90

In order that the shaft may be locked in any vertical position to which it may be moved by rocking the hand lever 13, we provide the guide 17 with holes 22, with which is adapted to engage a spring actuated sliding bolt 23 of known type actuatable through the medium of the connecting rod 24 from the lever grip 25 fulcrumed adjacent the grip end of the hand lever 13. 95

From the construction described it follows 100 that the reel may be adjusted vertically by rocking the bail-shaped frame through the medium of the hand lever 13, the frame rocking on the upper end of the link 10 and in the bearing block 8. When the link is swung 105 backwards or forwards to adjust the fore-and-aft position of the reel, the bearing block 8 slides on the guide 7 but, at all times, adequate support is given to the outer end of the reel shaft. 110

What we claim is:

1. A harvester-binder; a rigid bail-shaped frame; a reel shaft journalled on the ends of the frame; supports for the frame adapted to permit the frame to rock on an axis intermediate of its cross member and the reel shaft and to be moved back and forth; and means for locking one side of the bail-shaped frame in any position to which it may be moved.
- 10 2. A harvester-binder provided at opposite ends of its grain deck with reel supports, one formed as a substantially vertical swinging link and the other provided with a substantially horizontal guide parallel to the plane of movement of the swinging link; a rigid
- 15 bail-shaped frame; a reel shaft journalled on the ends of the frame; a bearing slidable on the guide aforesaid, the bail-shaped frame being journalled in the bearing and in the swinging link aforesaid on an axis intermediate of the shaft and the cross member of the frame; means for locking the swinging link in any desired position within its range; and means for locking the side of the bail-shaped frame adjacent the link in any desired position when rocked on the axis aforesaid.

Signed at Toronto, Canada, this 22nd day of December, 1926.
